CONTAINER

John C. van Cleaf, Maplewood, N. J., assignor to
 Gaylord Container Corporation, St. Louis, Mo.,
 a corporation of Maryland

Application August 10, 1942, Serial No. 454,259

3 Claims. (Cl. 229—45)

This invention relates to containers, particularly shipping cartons of the type comprising a tray member and a cover member telescoped over said tray member. The invention has for its principal object to provide a simple and economical carton of the above type wherein the cover member cooperates with the tray member to firmly secure said members together and to seal, strengthen and stiffen the carton. The invention consists in providing two opposite side walls of the cover member with marginal flaps that are folded inwardly towards one another and adhesively secured flatwise to the bottom of the tray in edgewise abutting relation to one another and to the other two sides of said cover member. The invention also consists in the construction, combinations and arrangements of parts hereinafter described and claimed.

In the accompanying drawing, which forms part of the specification and wherein like symbols refer to like parts wherever they occur,

Fig. 1 is a perspective view of a sealed shipping carton embodying my invention.

Fig. 2 is a perspective view of the tray member of said carton.

Fig. 3 is a perspective view of the cover member of said carton.

Fig. 4 is a cross-sectional view, showing the positions of the tray and cover members before the side wall flaps of the cover member are secured to the tray member.

Fig. 5 is a cross-sectional view, showing the assembled tray and cover members inverted and the side wall flaps of said cover member folded down upon and secured flatwise to the bottom portion of said tray member to form the sealed carton, the section being taken on the line 5—5 in Fig. 1.

Fig. 6 is a central longitudinal section through the end portion of the sealed carton on the line 6—6 in Fig. 1; and

Figure 7 is a cross-sectional view, similar to Fig. 5, showing a modified cover member.

My shipping carton comprises an inner or tray member A and an outer or cover member B telescoped over said tray member, each of said members being made of bendable material, such as fiber or corrugated board. The tray member is made from a blank which is folded up around the bottom 1 of the tray as a basis to form side walls 2 and end walls 3; and the top 4, side walls 5 and end walls 6 of the cover member are likewise formed from a similarly folded cover blank. The corners of the tray are formed by folding end flaps or extensions 7 of the side walls 2 in-

wardly to lie against the inner faces of end walls 3 and by folding marginal extensions or flaps 8 of said end walls downwardly and inwardly against said inwardly bent side wall flaps. The corners of the cover member B are formed in a similar manner; that is, by providing the end walls 6 with marginal flaps 10 that are rebent on the inner sides of said walls to hold the inwardly bent end flaps 9 of the side walls 5 between said end walls and the folded marginal flaps thereof.

The cover member B fits snugly over the tray member A of the carton; and the side walls 5 of said cover member have marginal flaps or extensions 11 that are folded inwardly upon the exposed surface of the bottom 1 of said tray member and are adhesively or otherwise rigidly secured flatwise thereto, said flaps being preferably in edgewise abutting relation along the longitudinal center line of the carton. If desired, the joint between the abutting edges of the side wall flaps 11 of the cover member B may be sealed by means of a strip 12 of gummed tape. As shown on the drawing, the end walls 6 of the cover member B are of slightly greater depth than the side walls 5 thereof so that the side wall flaps 11 fit between and are disposed in endwise abutting relation to the projecting folded edges of said end walls.

The articles or materials that are to be packed are placed in the tray member A of the carton and the cover member B is then telescoped over said tray member, after which the assembled members are inverted and the side marginal flaps 11 of said cover member folded down upon and adhesively secured flatwise to the bottom portion of the inverted tray. By this arrangement, the folded side wall flaps 11 of the cover member B serve to lock the tray member A therein; they also serve as sealing members for the carton; and they also function as struts and tie members that cooperate with the bottom portion 1 of said tray member to strengthen and stiffen the carton both longitudinally and transversely. The folded marginal edges of the end walls 6 of the cover B terminate beyond the plane of the bottom 1 of the tray member B; and the folded side wall flaps 11 of said cover member fit snugly between said end walls in endwise abutting relation thereto, thereby resisting any tendency for the side cover flaps to slide longitudinally relative to each other and to the tray member and throw the carton out of square.

Obviously, the side marginal flaps 11 of the cover member B may be spaced apart along their adjacent side edges and held in place by means

other than adhesive. Also, as shown in Fig. 7, said cover member may be provided with wide side marginal flaps 11a which are lapped one over the other and adhesively or otherwise held in place. Also, the end constructions of the tray member A and the cover member B may be varied without departing from the invention.

What I claim is:

1. A carton comprising a tray member and a cover member telescoped over said tray member, said cover member having flaps along the margins of the side walls only thereof that are folded over the bottom of said tray member and are adhesively held in place, said cover member having end walls that terminate beyond the bottom of said tray member substantially flush with the exposed faces of the folded side wall flaps of said cover member, said folded side wall flaps of said cover member extending continuously from end wall to end wall thereof between and in endwise abutting relation to the projecting portions of said end walls.

2. A carton comprising a tray member and a cover member telescoped over said tray member, said cover member having flaps along the margins of the side walls only thereof that are folded inwardly towards one another and are ad-

hesively secured flatwise to the bottom of said tray in sidewise abutting relation to one another, said cover member having end walls that terminate beyond the bottom of said tray member substantially flush with the exposed faces of the folded side wall flaps of said cover member, said folded side wall flaps of said cover member extending continuously from end wall to end wall thereof between and in endwise abutting relation to the projecting portions of said end walls.

3. A carton comprising a tray member and a cover member telescoped over said tray member, said cover member having flaps along the margins of the side walls only thereof that are folded inwardly one over the other and adhesively secured flatwise together and to the bottom of said tray, said cover member having end walls that terminate beyond the bottom of said tray member substantially flush with the exposed face of the outermost folded side wall flap of said cover member, said folded side wall flaps of said cover member extending continuously from end wall to end wall thereof between and in endwise abutting relation to the projecting portions of said end walls.

JOHN C. VAN CLEAF.
